(57) **CLAIM**

The ornamental design for an integrated long-sleeved smock and high chair tray cover, as shown and described.

DESCRIPTION

FIG. 1 is a front perspective view of an integrated long-sleeved smock and high chair tray cover, showing my new design in a condition of use;

FIG. 2 is a rear perspective view thereof, illustrated in a flat position;

FIG. 3 is a rear elevational view of FIG. 2;

FIG. 4 is a front elevational view of FIG. 2;

FIG. 5 is a bottom plan view of FIG. 2;

FIG. 6 is a top plan view of FIG. 2;

FIG. 7 is a left-side elevational view of FIG. 2;

FIG. 8 is a right-side elevational view of FIG. 2;

FIG. 9 is a rear perspective view of a second embodiment thereof;

FIG. 10 is a rear elevational view of FIG. 9;

FIG. 11 is a front elevational view of FIG. 9;

FIG. 12 is a bottom plan view of FIG. 9;

FIG. 13 is a top plan view of FIG. 9;

FIG. 14 is a left-side elevational view of FIG. 9; and,

FIG. 15 is a right-side elevational view of FIG. 9.

The broken lines showing a child and a high-chair in FIG. 1 depict environmental matter and form no part of the claimed design. The dot-dash broken lines in FIGS. 6 and 13 represent unclaimed portions of the inside surface of the integrated long-sleeved smock and high chair tray cover that form no part of the claimed design. The remaining broken lines represent stitching, and are part of the claimed design.
